COMBINED TUBE BRUSHING AND CLEANING MACHINE

Heinrich H. Frank, 508 Debby Lane, Elyria, Ohio

Filed Jan. 30, 1962, Ser. No. 68,574

Term of patent 14 years

(Cl. D37—1)

FIG. 1 is a front perspective view of a combined tube brushing and cleaning machine showing my new design; FIG. 2 is a rear perspective view.

The conventional electrical cord is fragmentarily shown in FIGS. 1 and 2 for convenience of illustration only.

The side opposite to that shown in FIG. 2 is the same except for the omission of the toggle switch. The legs are broken away to show indeterminate length.

I claim:

The ornamental design for a combined tube brushing and cleaning machine, as shown and described.
